(57) CLAIM

The ornamental design for two-tier storage rack, as shown and described.

DESCRIPTION

FIG. 1 is a front perspective view of the two-tier storage rack of the present invention showing the storage rack in the stored position;

FIG. 2 is a right side plan view of the two-tier storage rack of FIG. 1;

FIG. 3 is a left side plan view of the two-tier storage rack of FIG. 1;

FIG. 4 is a rear elevational view of the two-tier storage rack of FIG. 1;

FIG. 5 is a front elevational view of the two-tier storage rack of FIG. 1;

FIG. 6 is a top plan view of the two-tier storage rack of FIG. 1;

FIG. 7 is a bottom plan view of the two-tier storage rack of FIG. 1;

FIG. 8 is a front perspective view of the two-tier storage rack of the present invention showing the storage rack in the extended position;

FIG. 9 is a right side plan view of the two-tier storage rack of FIG. 9;

FIG. 10 is a left side plan view of the two-tier storage rack of FIG. 9;

FIG. 11 is a rear elevational view of the two-tier storage rack of FIG. 9;

FIG. 12 is a front elevational view of the two-tier storage rack of FIG. 9;

FIG. 13 is a top plan view of the two-tier storage rack of FIG. 9; and,

FIG. 14 is a bottom plan view of the two-tier storage rack of FIG. 9.

The dashed lines in the figures illustrate unclaimed subject matter and form no part of the claimed design.

1 Claim, 14 Drawing Sheets
